UNITED STATES PATENT OFFICE.

SIDNEY FLACK, OF ERIE, PENNSYLVANIA, ASSIGNOR OF ONE-FOURTH TO FREDERICK W. FLACK, ONE-FOURTH TO FRANK VITRON, AND ONE-FOURTH TO JOSEPH VITRON, OF ERIE, PENNSYLVANIA.

SANITARY COVER FOR TRANSMITTER-MOUTHPIECES.

1,370,104.

Specification of Letters Patent. Patented Mar. 1, 1921.

Application filed December 11, 1919. Serial No. 344,207.

To all whom it may concern:

Be it known that I, SIDNEY FLACK, a citizen of the United States, residing at Erie, in the county of Erie and State of Pennsylvania, have invented new and useful Improvements in Sanitary Covers for Transmitter-Mouthpieces, of which the following is a specification.

The purpose of the invention is to provide the mouth-piece of a telephone transmitter with a sanitary surface formed of such material as to sterilize any germ that may be deposited on the mouth-piece.

The invention is illustrated in the accompanying drawing wherein a telephone transmitter is shown in elevation, the mouth-piece being in section.

1 marks the transmitter and 2 the usual mouth-piece.

20 I form a detachable cover 3 for the interior surface of the mouth-piece made up of a disinfecting material, I have found that naphthalene is desirable for this purpose as this has the sterilizing quality and is susceptible of being molded to the proper shape. I prefer to provide a backing 4 for this covering 3 of metal and as the covering 3 is formed the metal forms one part of the mold and the sterilizing material adheres 30 to it.

The cover is so shaped as to make a close fit with the inner surface of the mouth-piece and is detachably secured therein by an annular clip 5 having a spring lip 6 which 35 snaps over the outer periphery of the

mouth-piece and holds the sterilizing cover 3 in place with a spring-pressed pressure so that there is no interference with the efficiency of the mouth-piece in the transmission of messages through the transmitter.

40

What I claim as new is:—

1. A sanitary cover for transmitter mouth pieces comprising a covering formed of sterilizing material and conforming in general contour to the interior surface of the mouth-piece, said covering being separately formed and detachable from the mouth-piece; and an annular ring arranged on the periphery of the mouth-piece for securing the cover in place, said ring engaging only the outer 50 edge of the cover whereby the greater portion of the sanitary covering may be exposed.

2. A sanitary cover for transmitter mouth-pieces comprising a covering formed of sterilizing material and conforming in general contour to the interior surface of the mouth-piece, said covering being separately formed and detachable from the mouth-piece; and an annular clip having a spring lip engaging the periphery of the mouth piece and securing the covering in the mouth-piece with a spring-pressed engagement, said clip engaging only the outer portion of the covering whereby the greater portion of said 60 covering is exposed.

In testimony whereof I have hereunto set my hand.

SIDNEY FLACK.
